UNITED STATES PATENT OFFICE.

HENRY W. HENNEBERG, OF CHICAGO, ILLINOIS.

GOLF-CADDIE-BAG STAND.

1,181,007.

Specification of Letters Patent.

Patented Apr. 25, 1916.

Application filed November 1, 1915. Serial No. 59,130.

To all whom it may concern:

Be it known that I, HENRY W. HENNEBERG, a citizen of the United States, residing at Chicago, in the county of Cook and State of Illinois, have invented certain new and useful Improvements in Golf-Caddie-Bag Stands; and I do declare the following to be a full, clear, and exact description of the invention, such as will enable others skilled in the art to which it appertains to make and use the same.

This invention relates to a folding trans- portable stand and more particularly to a stand for golf caddie bags.

The object of the invention is to provide a stand of this character so constructed that when brought into contact with a suitable surface the supporting members will be automatically extended into operative posi- 10 tion and when the bag is lifted they will automatically retract or collapse.

Another object is to provide a stand of this character, the operating member of which is telescopically mounted to position it out of the way when the bag is not in use and equipped with means for holding it in projected position.

With these and other objects in view, the invention resides in certain novel features of construction, combination and arrangement of parts to be hereinafter more fully described and claimed.

In the accompanying drawings: Figure 1 represents a side elevation of this improved stand applied; and in closed position; Fig. 2 is a rear elevation thereof with the stand collapsed; Fig. 3 is a side elevation showing the stand in open operative position; Fig. 4 is a rear view thereof with one leg broken off for convenience in illustration; Fig. 5 is a side elevation partly in longitudinal section showing the stand collapsed; Fig. 6 is a detail transverse section taken on the line 6—6 of Fig. 2.

In the embodiment illustrated a golf caddie bag B of usual construction is shown having an ordinary strap S for carrying the bag from place to place, and a band B' of rigid material secured to its inner face intermediately of its ends for holding the bag against twisting or collapse.

The stand constituting this invention is shown attached to this bag B and comprises a guide rod 1 having an eye 2 at its upper end which is secured to the upper end of the bag by a screw or any suitable fastening

means, and this rod extends throughout the length of the bag forming a reinforcing and stiffening member therefor, the lower end being secured by a clip 3 here shown 60 U-shaped in form with laterally extending feet 4 secured to the lower end of the bag, said clip extending loosely around the lower end of the guide rod and the parts mounted thereon, as will be hereinafter more fully 65 described.

A bracket or casting 5 has a bore 6 ex- tending edgewise therethrough in which said rod 1 is mounted to slide and is held therein by means of a set screw 7 to provide for the 70 adjustment of the casting at any desired point on the rod. This casting has attach- ing feet 8 through which connecting ele- ments 9 pass for securing it to the band B' which holds the bag against collapse. Ar- ranged between the bore 6 of the casting and the feet 8 on opposite sides thereof are two 75 bearings 9' and 10, both of which are exactly alike and are spaced from the bore 6 the same distance so that the guide rod 1 and 80 the supporting legs which are mounted in these bearings will be spaced substantially the same distance apart, although not neces- sarily so. These bearings 9' and 10 com- 85 prise longitudinally spaced laterally extend- ing lugs or flanges 11 which are provided with registering apertures 12 through which pass pintles 13 which pivotally connect the upper ends of legs 14 and 15 to the bracket. These bearings are elongated as shown to 90 hold the legs against spreading, said lugs being longer at their lower than at their upper edges. These legs 14 and 15 are here shown in the form of rods having weights 95 in the form of ball-like feet 16 at their lower ends which support the legs when in open position, and also assist in causing them to close when the bag is lifted.

Links 17 and 18 are pivotally connected at one end to the legs 14 and 15 preferably 100 at points near their upper ends, and the other ends of these links 17 and 18 are pivotally connected to the opposite sides of a collar 20 carried by the upper end of a sleeve 21 which is slidably mounted on the 105 lower end of the guide rod 1. As shown, these links 17 and 18 are of a length corre- sponding to the distance between their pivotal connection with the legs or rods 14 and 15 and the upper ends of said legs, so 110 that when the members are in open operative position the supporting ends of the legs will

be properly positioned in relation to the bag to hold it reliably in upright position and prevent all danger of its wobbling or falling over.

- 5 The sleeve 21 which is mounted to slide on the rod 1 has a stud 22 extending laterally therefrom, said stud being here shown disposed at a point below the center or mid-length of said sleeve.
- 10 An outer casing or sleeve 23 is mounted to slide on the sleeve 21 and to form an extension thereof, being provided at its lower end with a rounded ball-like foot 24 which is designed to engage a supporting surface when the device is in operative position. This sleeve 23 has a longitudinally extending slot 25 therein with an arm 26 extending laterally and downwardly from its upper end which, in connection with the stud 22 which is designed to operate in said slot, forms a bayonet-like connection between the sleeves 21 and 23, it of course being understood that when the stud 22 is in the lateral extension or arm 26 of the slot that said sleeve 23 will be locked against longitudinal movement and held in projected position relative to the sleeve 21 and when in this position the foot 24 thereof will extend below the lower end of the caddie bag B to adapt it for contact with a supporting surface before the bag is engaged therewith, as will be presently described.
- 15 A coiled spring 27 is mounted on the guide rod 1 between the lower face of the bracket 5 and the inner end of the collar 20 on the sleeve 21 and which is designed to exert its tension to normally force said sleeve outwardly, and to be compressed by the inward movement of said sleeve.
- 20 In the use of this improved stand, when the parts are in collapsed position as shown in Fig. 2, the sleeve 23 is moved inwardly to its extreme limit which is controlled by the engagement of the stud 22 with the outer end of the slot 25. To position the parts to adapt them to open for use on the placing of the caddie bag on the ground, the sleeve 23 is moved outwardly until the inner end thereof is engaged by the stud 22, then said sleeve is given a lateral turn in a direction to cause the slot arm 26 to engage the stud 22, and when in this position the sleeve 23 will be locked in relation to the sleeve 21, with the foot 24 thereof projecting beyond the bag B. When the bag is placed on the ground or other supporting surface, this foot 24 will first come in contact with said surface and under the weight of the bag and its contents will be moved longitudinally inward, thereby forcing the sleeve 21 upwardly and thus opening the legs 14 and 15 by means of the spreading of the links 17 and 18 and simultaneously compressing the coiled spring 27. The inward movement of the sleeve 23 is controlled by the engage-

ment of the ball-like foot 24 thereof with the clip 3 disposed at the lower end of the bag B, and when said foot reaches this clip, the legs 14 and 15 will have been spread outwardly in operative position as shown in Fig. 1, whereby the stand will reliably support the bag in position to afford ready access to the contents thereof. When it is desired to move the bag, the strap 8 is grasped and the bag lifted, and immediately on the lifting thereof the spring 27 will exert its tension to force the sleeve 21 outward, thereby moving the links 17 and 18 inward and thus retracting the legs 14 and 15, and when in this position the legs 14 and 15 will be disposed substantially parallel with the rod 1 on opposite sides thereof with the links similarly disposed between said legs, thus causing the parts of the stand to be disposed in compact relation and occupying very small space. The foot 24 of the sleeve 23 will, when in this position, project beyond the lower end of the bag B and if the bag is again to be set up, this foot is allowed to remain in this position, so that when it engages a supporting surface it will be moved inward and cause the legs to open outwardly in the manner above described. If, however, the bag is not to be again used, the sleeve 23 is turned to disengage the slot 25 arm 26 thereof from the stud 22 and said sleeve is moved inwardly to its extreme limit, and when said stud 22 engages the outer end of the slot 25 the foot 24 will be forced between the ball-like feet 16 of the legs 14 and 15 which are disposed on opposite sides of the foot 24, and thereby reliably engage said foot 24 and hold it clamped in retracted position. This clamping action of the feet 16 of the legs 14 and 15 is caused by the fact that the legs 14 and 15 are bowed slightly outward throughout their length so that when closed the ball-like feet thereof will lie flat and in yieldable engagement with the lower end of the caddie bag, and the foot 24 which is larger in diameter than the normal space between the feet 16, will force said feet laterally away from each other and thus cause them to exert a clamping engagement on said foot for reliably holding it in retracted position.

From the above description it will be obvious that this improved stand, while operating with efficiency to automatically open on the placing of the bag on the ground and to close on the lifting of the bag therefrom, is yet very simple in construction and may be disposed in a very small space when collapsed.

I claim as my invention:

1. A caddie bag stand comprising a supporting and guiding rod, means for connecting said rod to a bag, legs pivotally mounted at one end on said rod at opposite sides thereof, a spring pressed sleeve slid-

ably mounted on said rod, links connecting said sleeve with said legs, said sleeve having a projectable and retractable extension, and means on said legs for holding said sleeve 5 extension in retracted position.

2. A caddie bag stand comprising a supporting and guiding rod, means for connecting said rod to a bag, legs pivotally mounted at one end on said rod at opposite 10 sides thereof, a spring pressed sleeve slidably mounted on said rod, links connecting said sleeve with said legs, said sleeve having a projectable and retractable extension, said extension having a rounded foot at its outer 15 end, said legs having similarly shaped feet on their free ends positioned on opposite sides of said sleeve when in collapsed position and spaced apart a distance less than the diameter of the foot on said sleeve, 20 whereby on the forcing of said foot between said legs it will be reliably clamped in retracted position.

3. A caddie bag stand comprising a guide rod having bag attaching means at one end, 25 a sleeve mounted to slide on said rod, an attaching bracket secured to said rod, a coiled spring mounted on said rod between said bracket and sleeve, legs pivotally mounted at one end on said bracket on opposite sides 30 of said rod, links pivoted at one end to said legs and at the other end to said sleeve, and an extension sleeve telescopically engaged with said first mentioned sleeve, said sleeves having coöperating means for locking the 35 extension sleeve in projected position.

4. A caddie bag stand comprising a guide rod having bag attaching means at one end, a sleeve mounted to slide on said rod, an attaching bracket secured to said rod, a coiled 40 spring mounted on said rod between said bracket and sleeve, legs pivotally mounted at one end on said bracket on opposite sides of said rod, links pivoted at one end to said legs and at the other end to said sleeve, and 45 an extension sleeve telescopically engaged with said first mentioned sleeve, said sleeves having coöperating means for locking the extension sleeve in projected position, and coöperating means on said legs and said 50 extension sleeve for locking the latter in retracted position.

5. A caddie bag stand comprising a guide rod having a bag attaching means at one end, a sleeve mounted to slide on said rod,

an attaching bracket secured to said rod, a 55 coiled spring mounted on said rod between said bracket and sleeve, legs pivotally mounted at one end on said bracket on opposite sides of said rod, links pivoted at one end to said legs and at the other end to said sleeve, and an extension sleeve telescopically engaged with said first mentioned sleeve, one of said sleeves having a laterally extending stud and the other having a longitudinally extending slot, 65 with a lateral arm at its inner end for connecting said extension sleeve in projected position.

6. A caddie bag stand comprising a guide rod, means for attaching said rod to a caddie bag, a bracket adjustably mounted on said rod with arms extending on opposite sides of said rod, legs pivotally mounted on said arms, said legs being bowed slightly outward, a spring projected sleeve mounted 75 on said rod, links connected at one end to said sleeve and at their other ends to said legs near their upper ends, an extension sleeve telescopically engaged with said first 80 mentioned sleeve, and coöperating means on the ends of said extension sleeve and said legs for locking said extension sleeve in retracted position.

7. A caddie bag stand comprising a guide rod, an arcuate casting having a bore extending transversely thereof midway its ends to receive said rod, means for adjustably connecting said rod and casting, a pair of laterally extending apertured lugs projecting from said casting at each side of the bore 90 thereof, the lugs of each pair being spaced apart to form bearings, said lugs being longer at their lower than at their upper edges, legs having one end pivotally mounted in said bearings, a spring pressed sleeve 95 slidably mounted on said rod, links connecting said sleeve with said legs, said sleeve having a projectable and retractable extension, and means on said legs for holding said sleeve extension in retracted position. 100

In testimony whereof I have hereunto set my hand in presence of two subscribing witnesses.
